(57) **CLAIM**

We claim the ornamental design for a housing for a hooded interactive aerial display system, as shown and described.

DESCRIPTION

FIG. 1 is a front isometric view of a housing for a hooded interactive aerial display system;

FIG. 2 is a rear isometric view thereof;

FIG. 3 is a front elevation view thereof;

FIG. 4 is a left side view thereof (right being mirror image);

FIG. 5 is a top view thereof; and,

FIG. 6 is a rear view thereof.
